UNITED STATES PATENT OFFICE.

WILLIAM R. McKEEN, JR., OF OMAHA, NEBRASKA, AND FRANK S. BARKS, OF ST. LOUIS, MISSOURI, ASSIGNORS TO RAILROAD WEED BURNER COMPANY, OF ST. LOUIS, MISSOURI, A CORPORATION OF DELAWARE.

VEGETATION-DESTROYER.

No. 877,515.

Specification of Letters Patent.

Patented Jan. 28, 1908.

Application filed November 18, 1907. Serial No. 402,755.

To all whom it may concern:

Be it known that we, WILLIAM R. McKEEN, Jr., and FRANK S. BARKS, citizens of the United States, residing, respectively, at 5 Omaha, in the county of Douglas and State of Nebraska, and at St. Louis, in the State of Missouri, have invented a new and useful Improvement in Vegetation-Destroyers, of which the following is a specification.

10 Our invention relates to that class of vegetation-destroyer in which an arrangement of gasolene tanks and burners combined with a suitable motor and other appurtenances are carried by a frame or vehicle mounted on 15 wheels and propelled along a railroad track for burning the weeds along and on each side of the same, and is in the nature of an improvement on the United States Letters Patent granted to William R. McKeen, Jr., 20 and Arthur H. Fetter, January 23, 1906, Number 810,793, for improvement in vegetation-destroyers.

Our invention has for its object to increase the intensity and efficiency of the burner 25 flame and utilize the heat therefrom for vaporizing the gasolene in its passage to the burners.

The invention consists in features of novelty as hereinafter described and claimed, reference being had to the accompanying drawing forming part of this specification, whereon,

Figure 1, is a top plan view of a series of gasolene burners with their combined casing or deflector and vaporizing pipes (indicated by dotted lines) constructed and arranged according to our invention; Fig. 2, a side elevation thereof; Fig. 3, a vertical cross section to enlarged scale through one of the burners and combined parts, on line 3, 3, in 40 Fig. 1 and Fig. 4, a top plan view thereof, broken away.

Like letters and numerals of reference denote like parts in all the figures.

a represents an end portion of the frame or 45 vehicle, and *b* the corresponding wheels of a vegetation-destroyer of the character described, in which the gasolene tank or reservoir, motor, and other necessary equipment (not shown), being of the usual construction 50 and constituting no part of our present invention needs no further description.

Extending horizontally beyond the end portion *a* of the frame or vehicle (hereinafter referred to as the frame), over and between

the rails of the track *c* at a suitable distance 55 therefrom, is a preferably, shallow rectangular casing or deflector *d* which is adjustably secured to the end of the frame *a* by brackets or hangers *e* fixed at their lower ends to the top of the casing *d*, preferably by rivets 1, 60 and at their upper ends to the end of the frame *a* by bolts 2, the holes for the latter through the end member of the frame *a* and the brackets *e* respectively, being at equal distances apart so that on removing the 65 bolts 2, the casing *d* can be raised or lowered, and refixed by the bolts 2, at varying distances from the track *c* as desired.

To each side of the casing *d* is hinged a similar casing or deflector *d'* which is adjustable to a suitable distance from the surface of the ground adjacent to the corresponding side of the track *c*, the casings *d* and *d'* being preferably open at the bottom, but otherwise closed on all sides, except at the top, through which are formed preferably, circular openings 3 at a suitable distance apart.

Through each opening 3 is removably inserted a correspondingly shaped burner tube 4 (see Figs. 3 and 4) which depends for a 80 suitable distance within the casing *d* (*d'*) and is preferably formed at its upper end with an outer surrounding flange or lip 4' which bears on the top of the casing *d* (*d'*) and makes an air-tight joint therewith. Within each casing *d*, *d'*, is arranged a pipe 5 (or series thereof communicating with each other) which is preferably, bent or otherwise directed to and fro, around and adjacent to, but clear of, the burner tubes 4 as shown, and held and tightened against the inside of the top of the casing *d* (*d'*) by clamps or staples 6, the prongs of which pass through, and are, clenched against the outside of the top of, the casing *d* (*d'*) by nuts 6'. Or the pipe 5 may be otherwise arranged and secured at a suitable level within the casing *d* (*d'*) in any other desired manner. Or in lieu of a pipe 5, any other form of receptacle or chamber secured to, or integral with the walls of the 90 casings *d*, *d'* may be used as the equivalent thereof.

The pipe 5 of each casing *d*, *d'*, communicates at one end with a gasolene tank or reservoir (not shown) carried on the frame *a* as 105 before mentioned, by a pipe 5', between which and the pipe 5 is an universal joint 7 to allow for the said adjustments of the cas-

ings d , d' , while the other end of each pipe 5 communicates by means of a suitable elbow 8 with a series of pipes 9 which are arranged over and adjacent to the top of each casing 5 d , d' , as shown.

Projecting from and communicating with the pipes 9 on their underside immediately over each burner tube 4, is a nipple 10 (see Figs. 3 and 4) the passage-way through which from the interior of the pipes 9 to its outlet into the upper open end of the tube 4 is packed with fine wire netting or other suitable permeable material 11 adapted to filter the gasoline vapor in passing therethrough as hereinafter referred to.

In the operation of our improved apparatus, as above described, gasoline (or other liquid fuel) being admitted from the tank or reservoir on the frame a through the pipes 5 into the pipes 5 inclosed by the casings d , d' , heat from any available source is initially applied to the pipes 5 and thereby vaporizes or converts the gasoline therein into gas which passes from the pipes through the gas pipes 9, and thence through the nipples 10 (wherein it is strained by the packing 11) into the burner tubes 4, and in so doing air is drawn by the induced current from the spaces between the tubes 4 and nipples 10, and mixing with the gas passes therewith through the burner tubes 4, at the lower ends of which, or thereabout, within the casings d , d' , the resulting mixture is ignited and an intense heat thereby generated, which being deflected downward by the top of the casings d , d' , is concentrated upon and destroys the vegetation beneath as the frame or vehicle carrying the apparatus travels along the track, and at the same time maintains the constant vaporization of the gasoline within the pipes 5 during the operation.

By this invention the flame from the burners is intensified and being confined within the casings or deflectors d , d' , and utilized for vaporizing the gasoline instead of being dispersed or dissipated into the surrounding atmosphere, its efficiency is greatly increased; moreover, the vegetation is destroyed more thoroughly and uniformly, with less risk to the gasoline tanks and other apparatus on the frame or vehicle.

What we claim as our invention and desire to secure by Letters Patent is:

1. In a vegetation-destroyer of the character described, the combination with a frame or vehicle adapted to travel along a railroad track, of a casing or deflector adjustably secured to the frame over, and between the rails of the track, a receptacle within the casing adapted to contain liquid fuel, means for supplying the receptacle with the said fuel from a suitable reservoir carried by the frame, a burner tube projecting through the top wall of, and into the casing adjacent to the receptacle, and having its inlet and outlet on the outside and inside respectively, of the casing, a pipe on the outside of the casing adjacent to the said inlet and communicable with the receptacle, and a nipple on the pipe opening therefrom into the said tube, substantially as described and for the purpose set forth.
2. In a vegetation-destroyer of the character described, the combination with a frame or vehicle adapted to travel along a railroad track, of a casing or deflector adjustably secured to the frame over, and between the rails of the track, a receptacle within the casing adapted to contain liquid fuel, means for supplying the receptacle with the said fuel from a suitable reservoir carried by the frame, a burner tube projecting through the top wall of, and into the casing adjacent to the said inlet and communicable with the receptacle, and a nipple on the pipe opening therefrom into the said tube, substantially as described and for the purpose set forth.
3. In a vegetation-destroyer of the character described, the combination with a frame or vehicle adapted to travel along a railroad track, of a casing or deflector adjustably secured to the frame over, and between the rails of the track, and open at the bottom opposite to the ground between the said rails, a receptacle within the casing adapted to contain liquid fuel, means for supplying the receptacle with the said fuel from a suitable reservoir carried by the frame, a burner tube projecting through the top of, and into the casing adjacent to the receptacle, and having its inlet and outlet on the outside and inside respectively, of the casing, a pipe on the outside of the casing adjacent to the said inlet and communicable with the receptacle, and a nipple on the pipe opening therefrom into the said tube, substantially as described and for the purpose set forth.
4. In a vegetation-destroyer of the character described, the combination with a frame or vehicle adapted to travel along a railroad track, of a casing or deflector adjustably secured to the frame over, and between the rails of the track, and open at the bottom opposite to the ground between the said rails, a receptacle within the casing adapted to contain liquid fuel, means for supplying the receptacle with the said fuel from a suitable reservoir carried by the frame, a burner tube projecting through the top wall of, and into the casing adjacent to the receptacle, and having its inlet and outlet on the outside and inside respectively, of the casing, a pipe on the outside of the casing

adjacent to the said inlet and communicable with the receptacle, a nipple on the pipe opening therefrom into the said tube, and a packing of permeable material between the 5 said reservoir and the outlet of the nipple, substantially as described and for the purpose set forth.

5. In a vegetation-destroyer of the character described, the combination with a 10 frame or vehicle adapted to travel along a railroad track, of a casing or deflector adjustably secured to the frame over, and between the rails of the track, a casing hinged to and radially adjustable about the first- 15 named casing over the ground at the side of the track, a receptacle within each of the said casings adapted to contain liquid fuel, means for supplying the receptacles with the said fuel from a suitable reservoir carried by the frame, a burner tube projecting through the top wall of, and into each casing adjacent to the receptacle, and having its inlet and 20 outlet on the outside and inside respectively, of the casing, a pipe on the outside of the 25 casing adjacent to the said inlet and communicable with the receptacle, and a nipple on the pipe opening therefrom into the said tube, substantially as described and for the purpose set forth.

30 6. In a vegetation-destroyer of the character described, the combination with a frame or vehicle adapted to travel along a railroad track, of a casing or deflector adjustably secured to the frame over, and between the rails of the track, a casing hinged to and radially adjustable about the first-named casing over the ground at the side of the track, a receptacle within each of the said casings adapted to contain liquid fuel, means 35 for supplying the receptacles with the said fuel from a suitable reservoir carried by the frame, a burner tube projecting through the top wall of, and into each casing adjacent to the receptacle, and having its inlet and outlet on the outside and inside respectively, of the casing, a pipe on the outside of each casing adjacent to the said inlet and communicable with the receptacle, a nipple on the pipe opening therefrom into the 40 said tube, and a packing of permeable material between the said reservoir and the outlet of the nipple, substantially as described and for the purpose set forth.

45 7. In a vegetation-destroyer of the character described, the combination with a frame or vehicle adapted to travel along a railroad track, of a casing or deflector adjustably secured to the frame over, and between the rails of the track, and open at the bottom 50 opposite to the ground between the said rails, a casing hinged to and radially adjustable about the first-named casing and open at the bottom opposite to the ground at the side of the track, a receptacle within each of the 55 said casings adapted to contain liquid

fuel, means for supplying the receptacles with the said fuel from a suitable reservoir carried by the frame, a burner tube projecting through the top wall of, and into each casing adjacent to the receptacle, and having its inlet and outlet on the outside and inside respectively, of the casing, a pipe on the outside of each casing adjacent to the said inlet and communicable with the receptacle, and a nipple on the pipe opening therefrom into the 70 said tube, substantially as described and for the purpose set forth.

8. In a vegetation-destroyer of the character described, the combination with a frame or vehicle to travel along a railroad 80 track, of a casing or deflector adjustably secured to the frame over, and between the rails of the track, and open at the bottom opposite to the ground at the side of the track, a receptacle within each of the said casings adapted to contain liquid fuel, means for supplying the receptacles with the said fuel from a suitable reservoir carried by the frame, a burner tube projecting through the top wall of, and into each casing adjacent to the receptacle, and having its 85 inlet and outlet on the outside and inside respectively, of the casing, a pipe on the outside of each casing adjacent to the said inlet and communicable with the receptacle, a nipple on the pipe opening therefrom into the 90 said tube, and a packing of permeable material between the said reservoir and the outlet of the nipple, substantially as described and for the purpose set forth.

9. In a vegetation-destroyer of the character described, the combination with a frame or vehicle adapted to travel along a railroad track, of a receptacle adjustably secured to the frame over the track and ground adjacent thereto, and adapted to contain liquid fuel, means for supplying the receptacle with the said fuel from a suitable reservoir carried by the frame, a burner tube adjacent to and communicable with the receptacle, and a packing of permeable material between the said reservoir and the outlet of the nipple, substantially as described and for the purpose set forth.

In testimony whereof we have signed our names to this specification in the presence respectively, of two subscribing witnesses.
